UNITED STATES PATENT OFFICE

HERBERT V. LEAHY, OF LOS ANGELES, CALIFORNIA

ATOMIZING OIL BURNER

Application filed March 16, 1929. Serial No. 347,524.

This invention relates to atomizing oil burners of the external and semi-internal atomizing type. An object of the present invention is ease of installation and removal.

5 5 A very important object is to prevent cracking of the oil within the burner, thereby insuring against a burner being clogged by hard carbon, which, as is well known, is hard to remove.

10 Another object is to make provision for location of the atomizing fluid supply line and oil line at minimum distances from the front of the furnace and at the same time to make provision whereby these lines will

15 always be in position with all piping tied together in a single unit so that said piping will be rigid and never in the way of the furnace attendant.

20 Another object is to provide a construction whereby a burner of this type may be caused to direct the flame at various angles without changing the position of the external piping and without the necessity of bending the pipes that lead to the burner head.

25 Another object is to provide a burner that can be disconnected from the atomizing fluid and fuel supply lines by loosening a single screw, thereby avoiding the use of unions and the operation of a wrench to disconnect the unions. This makes very simple the operations of connecting and disconnecting the burner.

30 Another important object is to effect cooling of the burner head by the atomizing fluid, thus eliminating one of the greatest faults found with other burners of this type, namely, carbonization and cracking of the parts. Carbonization of other burners of this type is caused by the heat reflected by the combustion chamber or fire box with which the burner functions.

35 Another object is the production of a burner of this type of comparatively simple construction and one in which the various parts can be readily replaced at a comparatively small cost.

40 Another object is to make provision for ready removal of the steam or air chamber, without the necessity of disturbing the oil

feed mechanism, so that said chamber can be cleaned.

45 Another object is to effect a change in the spread of the flame, to suit the various conditions under which the burner may be operated, by the adjustment of one part of the burner.

50 Another object is to provide a construction that makes it practically impossible for the various parts to be incorrectly assembled, thus eliminating the chance of there being leaks in the joints of the atomizing fluid and oil lines.

55 Another object is to provide a construction that makes it possible to use the same burner head for horizontal and vertical firing, and to obtain the same advantages in either case. This is quite important in the securing of low manufacturing cost.

60 Another object is to make provision for feed of the fuel upon the atomizing agent in an arc at a right angle to the direction of flow of the atomizing agent.

65 Another object is to make provision for feeding a predetermined amount of the atomizing agent to the oil slightly in advance of the impingement of the oil against the main stream of the atomizing agent, thus aiding in atomization of the oil into exceedingly fine particles.

70 Another object is to provide a construction which will admit of the substitution of deflecting elements of various shapes. By employing these elements in conjunction with the construction whereby a given amount of auxiliary atomizing agent is injected into the oil, the deflecting elements function to additionally mix the oil and atomizing agent externally of the burner, thus converting the burner into a semi-internal or inter-mixture atomizing type.

75 Another object is to provide a construction employing either a flat-faced or a beveled face ring, extending laterally beyond the oil feed port so as to secure a burner of the semi-internal or inter-mixture atomizing type with the additional advantage of effecting projection of the atomizing mixture, by use of the beveled face ring, downwardly at the angle of bevel of the ring.

Other objects and advantages will appear in the subjoined detailed description.

The accompanying drawings illustrate the invention:

5 Fig. 1 is a front elevation of an atomizing oil burner constructed in accordance with the provisions of this invention;

10 Fig. 2 is a vertical view, partly in section, from the line indicated by 2—2 Fig. 1, portions of the tubes being broken away to contract the view.

Fig. 3 is an enlarged fragmental vertical section on the line indicated by 3—3 Fig. 1.

15 Fig. 4 is a sectional view on the line indicated by 4—4 Fig. 3.

Figs. 5 and 6 are enlarged vertical sections on the lines indicated by 5—5, 6—6, respectively, Fig. 3.

20 Fig. 7 is a plan view of the burner head in Fig. 2, fragments of the tubes also being shown.

Fig. 8 is an enlarged fragmental vertical section on the line indicated by 8—8 Fig. 7.

25 Fig. 9 is an enlarged vertical section on the line indicated by 9—9 Fig. 7.

Fig. 10 is an enlarged fragmental vertical section on the line indicated by 10—10 Fig. 7.

Fig. 11 is a fragmental horizontal section on the line indicated by 11—11 Fig. 10.

30 Fig. 12 is a horizontal section on the line indicated by 12—12 Fig. 10.

Fig. 13 is a view similar to Fig. 11, showing a slightly modified form of the invention.

35 Fig. 14 is a horizontal section on the line indicated by 14—14 Fig. 13.

Fig. 15 is a view similar to Fig. 13 illustrating a still different form of the invention.

40 First, referring to Figs. 1 to 12 of the drawings, a burner head is indicated at 16 and is connected by oil and atomizing agent tubes 17, 18, respectively, to a by-pass which is formed in separable sections 19, 20 that are releasably clamped together by a yoke 21 and screw 22. The yoke 21 is pivoted at 45 23 to opposite sides of the section 19 and the screw 22 is screwed through the yoke and has its inner end engaging a seat 24 in the upper side of the section 20.

50 The opposite sides of the section 20 are provided with screw threaded openings 25, 26 and into said openings are screwed pipe lines 27, 28, respectively, the pipe 27 supplying oil and the pipe 28 supplying an atomizing agent such as steam or air. The opening 25 admits the oil to a passage 29 in the section 20, and the opening 26 admits the atomizing agent to a passage 30 in said section. The passages 29, 30 are separated from one another by a horizontal upper partition 31, a horizontal lower partition 32, and a vertical partition 33 that connects the partitions 31, 32. Thus, the oil enters the chamber 29 and passes upwardly, while the atomizing agent enters the passage 30 and flows 55 downwardly. Pipe line 27 connects with an

oil strainer 34 which may be of any suitable construction, and accordingly, not necessary to illustrate and describe in detail herein. The pipe line 28 is connected to any suitable source, not shown, of steam or compressed air supply. The lines 27, 28 are provided, respectively, with valves 35, 36 for controlling the fluid that passes through said lines.

70 The section 20 is provided at the lower end of the passage 29 with a threaded opening 37 into which is screwed a thimble 38 provided with an external annular shoulder 39 between which and the under face of the section 20 is interposed an internal flange 40 of a seat member 41. The outer face 42 of the seat member 41 is tapered to fit a tapered seat 43 in the wall of an opening 44 in the section 19, said opening 44 communicating with a passage 45 in said section 19.

75 The thimble 38 is provided with another external annular shoulder 46 which is spaced from the shoulder 39 a distance that is slightly greater than the thickness of the flange 40, and the seat member 41 is a loose fit on the thimble so that a certain amount of lateral motion can occur between the seat member and the thimble, thus enabling the seat member to automatically adjust itself so as to axially align with the seat 43, regardless of contraction and expansion of either of the sections 19, 20.

80 The bottom of the section 20 is provided with another screw threaded opening 47 that communicates with the lower end of the passage 30. In the opening 47 is screwed a seat member 48 which is provided with an outer tapered face 49 that fits a tapered seat 50 in the wall of an opening 51 in the section 19, said opening 51 communicating with a passage 52 in the section 19.

85 From the foregoing it will be readily understood that both seat members 41, 48 will at all times perfectly center within their seats, regardless of contraction or expansion of the sections 19, 20, since the seat member 41 can move laterally with respect to the thimble 38 or the thimble 38 laterally with respect to the seat member 41.

90 Communication may be opened between the passages 45, 52 by reason of a port 53 connecting said passages, and this port is controlled by a suitable valve 54 which is normally closed when the burner is in operation. To clean the burner, the valve 54 will be opened, thus permitting steam to flow through the oil tube 17 and through the oil passages in the burner head which will be hereinafter described. The tube 17 is screwed into a threaded opening 55 in the partition 56 that separates the passages 45, 52, said opening 55 thus communicating with the passage 45. The outer tube 18 that carries the atomizing agent is connected by a union 57 to a threaded boss 58 on the section 19, the tube 18

projecting into an opening 59 in the box, for opening communication with the passage 52. The union 57 is provided with packing 60 to prevent leakage.

The supply lines 27, 28 are secured by U-clips 61 and bolts 62 to a supporting plate A that may constitute a front wall plate of the furnace.

The burner head will now be described as follows:

The body of the burner head may be made in one piece, if desired, but, in the present instance, said body is of sectional construction in which there is a forward section 63 and a rear section 64, the section 63 being swiveled on the section 64 by a swivel joint 65, thus enabling the section 63 to be turned to different angular positions with respect to the tubes 17, 18 which support the burner head. Shoulders 66 on the section 64 limit angular movements of the section 63.

The section 63 is provided with separate passages 67, 68 which extend lengthwise therein. The passage 67 receives oil through a threaded opening 69 into which is screwed one end of the tube 17, and the passage 68 receives the atomizing agent through a threaded opening 70 into which is screwed the tube 18. It is to be particularly noted that the atomizing agent passage 68 extends along the upper side of the head section 64 and that the oil passage 67 extends along the lower side of said head section or, in other words, beneath the passage 68, thus materially shielding the oil against heat that may be reflected from the furnace onto the top of the head section 64. Also, it will be noted that the oil tube 17 lies within the atomizing agent tube 18 so that the atomizing agent protects the tube 17 from the heat radiated by the furnace.

The sections 63, 64, I provide with flat contacting faces 71, 72, respectively, and opening through the flat face 71 are ports 73, 74. Also opening through the flat face 72 are ports 75, 76 which are, respectively, alined at all times with the ports 73, 74, all of said ports being elongate so as to pass the atomizing fluid and the oil regardless of the angle at which the section 63 may be positioned with respect to the section 64.

The head section 63 is provided with lower and upper passages 77, 78 that communicate with the ports 73, 74 so that, in this case also, the atomizing fluid passage 78 is above the oil passage 77, thereby entailing that the oil passage is shielded by the atomizing fluid from heat reflected on the upper side of the head section 63 from the furnace walls.

In this instance, the faces 71, 72 are held in close contact by a bolt 761 which passes through solid hub portions 762, 763 of the head sections 63, 64, respectively, the hub portion 762 separating the port 73 from the port 74 and the passage 77 from the passage

78; and the hub portion 763 separating the port 75 from the port 76 and the passage 67 from the passage 68. The port 75 communicates with the passage 67 and the port 76 communicates with the passage 68.

The passage 78 terminates at its forward end in a circular bore portion 79 and said bore portion 79 terminates downwardly in an annular shoulder 80 against which seats a chambered cylindrical member 81 which is provided with a threaded stud 82 that projects upwardly through the bore portion 79 and through an opening 83 in the top of the head section 63. On the outer end of the stud 82 is threaded a nut 84 whereby the member 81 is pulled tight against the seat 80.

The member 81 is provided with a transversely extending passage 85 which communicates at its rear end with the passage 77 so as to form, in effect, a continuation of said passage 77. The forward end of the passage 85 communicates with a transversely extending segmental slot 86 which, in turn, communicates at its forward end with an arcuate vertical oil discharging slot 87 that is formed in the outer face of a bushing 88 that surrounds a portion 89 of the member 81, said portion 89 being of a reduced diameter. In other words, the upper end portion of the member 81 is provided with an external cylindrical flange 90 which fits a bore portion 91 of the head section 63, whereas the reduced portion 89 leaves an annular recess in which is disposed the bushing 88.

The bushing 88 is spaced somewhat from the flange 90 and said bushing is provided with an external flange 92, which seats against a lower face 93 of the head section 63. Projecting downwardly from the member 81, axially thereof, is a threaded stud 94 on which is screwed a nut 95 that bears against the under face of a ring 96 that is held against the lower end of the bushing 88 which projects some distance below the face 93. The ring 96 surrounds a reduced portion 97 of the nut 95. The lower end of the bushing 88 has a portion cut away to define an arcuate slot 98 lying between said bushing 88 and the ring 96, the atomizing fluid being adapted to discharge horizontally through said slot 98 so that the oil discharging through the arcuate slot 87 will impinge on the stream of atomizing fluid as said atomizing fluid issues from the slot 98. The upper face of the ring 96 is recessed at 981 so as to form, in conjunction with the bore of the bushing 88, an expansion chamber for the oil. The bore of the bushing 88 communicates with the chamber 79 through a vertical port or ports 99 in the member 81, said ports 99 passing on opposite sides of the passage 85 and being separated therefrom, as is clearly shown in Fig. 11. Thus, the atomizing fluid as it passes downwardly

121
122
123

through the ports 99 protects the oil in the passage 85 from heat reflected from the furnace onto the sides of the head section 63.

In order that the member 81, and bushing 88 may be easily assembled in proper position in the head section 63, I provide a pin 991 in the member 81, said pin projecting laterally from said bushing through a vertical slot 992 in the bushing 88 and into a vertical slot 993 in the head section 63, the slot 992 opening 10 to the bottom edge of the bushing and the slot 993 opening to the face 93 so that, in assembling, the member 81 and bushing 88 will first be telescoped and then the bushing, with the member 81 therein, will be slid into 15 the bore that is to receive it.

The form of the invention illustrated in Figs. 13 and 14 is very little different from the construction hereinbefore described and the parts that are the functional equivalent 20 of those above described are indicated by the same reference characters with the addition of the suffix a. In this form of the invention the vertical arcuate slot 87a communicates with the slot 86a, not only, but it is extended 25 upwardly past the flange 90a of the member 81a so as, also, to communicate with an arcuate opening 100 that is cut through said flange, thereby permitting a predetermined amount of atomizing fluid to discharge from 30 the bore portion 79a past the flange 90a into the upper end of the slot 87a. Because of the atomizing fluid discharging under higher pressure than the oil, it follows that, in this 35 form of the invention, the oil will be discharged from the slot 87a under a pressure substantially equal to the pressure of the atomizing fluid discharging from the slot 98a.

Consequently, the resulting mixture produced at the circular line of impingement of 40 the vertically and horizontally directed streams will be directed aslant downwardly and forwardly from the burner, and this angle of discharge of the mixture will be 45 governed more or less by the ring 96a which extends horizontally beyond the periphery of the bushing 88a. Thus the ring 96a is of 50 larger outside diameter than the ring 96 hereinbefore described. In this instance, the 55 ring 96a is provided with a downwardly and outwardly beveled upper face 101, it being understood that rings with faces of varying degrees of bevel may be associated with the head section 63 so as to thereby control, at least to some extent, the downward deflection of the combustible mixture.

The form of the invention illustrated in Fig. 15 follows very closely the construction illustrated in Figs. 13 and 14 and the elements that function the same are indicated by the same numeral portions of the reference characters with the addition of the suffix b. The only difference is that the ring 96b has 60 that portion of its upper face 101b, that extends beyond the periphery of the bushing 65

88b, substantially horizontal, thus preventing any material downward deflection of the combustible mixture produced by the burner.

The foregoing will make clear the construction and operation of the invention, and, 70 briefly stated, the operation is as follows:

The bushing 88, 88a or 88b, and ring 96, 96a or 96b having been installed, and the head section 63 having been suitably adjusted to the desired angle relative to the section 64, the 75 valves 35, 36 will be opened to admit the atomizing fluid and oil to the burner head by way of the pipe lines 27, 28, tubes 17, 18 and the various passages hereinbefore described. In the event of the assembly being that illustrated in Fig. 19, the oil will discharge from the slot 87 under relatively low pressure and impinge on the atomizing stream issuing from the slot 98, thereby producing a finely 80 atomized combustible mixture that is ignited and burned in a manner well understood in this art.

In event that the assembly is that of Fig. 13, a predetermined quantity of the atomizing fluid will mix to some extent with the oil in the slot 87a and the oil and steam will discharge from the slot 87a at the relatively high pressure of the steam. The downwardly directed oil and steam from the slot 87a will impinge upon the high pressure atomizing stream issuing from the slot 98a, thus further mixing the atomizing fluid and the oil and atomizing the oil, and the streams impinge upon the ring 96a, thereby still further atomizing the mixture.

In the event of the assembly being that of Fig. 15, the same results are secured as that described in connection with Fig. 13, excepting that the mixture will be discharged from the burner at right angles to the axis of the 105 bushing 88b.

Special attention is directed to the construction hereinbefore described whereby the bushing 81 is held tightly against the head section 63, thus making it impossible for 110 air or steam to leak around the ring and come in contact with the oil within the burner head.

Also, to be particularly noted, is the construction of the passage for the atomizing fluid at the top, the passage for the oil at the bottom, the ports at the side connecting these passages, and the oil passage located between the upper and lower passages, on the one hand, and between the ports 99, on 120 the other hand, thereby surrounding the oil, at that portion of the burner that is exposed to the highest temperature, with steam so that said oil will not be at a higher temperature than the steam and, accordingly, not 125 subjected to cracking temperatures that would tend to cause a deposition of hard carbon within that portion of the burner, thus making it difficult to clean.

Another point to be observed is that, be- 130

cause of the particular construction of the head section 63, member 81, bushing 88, and the studs 82, 94 and nuts 84, 95 for separately holding the member 81 and bushing 88 assembled with the head section 63, access may be had to the lower chamber for the atomizing fluid without disturbing the upper chamber for said fluid, and, also, access may be had to the upper chamber without disturbing lower chamber.

Because of the construction providing for the atomizing fluid passing from the upper chamber through ports into the lower chamber and through the port 100 in the flange 98, thence into the upper portion of the slot 87a, all parts of the burner head are maintained at a temperature approximately that of the atomizing agent.

I claim:

1. A coupling comprising separable sections, each section provided with separate passages, one of the sections being provided with openings communicating with its passages for connection with pipe lines, a means to clamp the sections together, one of said sections being provided with ports communicating with its passages, and the walls of said ports being provided with seats, and the other section being provided with openings communicating with its passages, and seat members surrounding said openings and releasably engaging said seats, one of said seat members being loosely connected with the section with which it is associated so as to be self-adjusting to the seat that it engages.

2. A coupling comprising separable sections, each section provided with separate passages, one of the sections being provided with openings communicating with its passages for connection with pipe lines, a means to clamp the sections together, one of said sections being provided with ports communicating with its passages, and the walls of said ports being provided with seats, and the other section being provided with openings communicating with its passages, and seat members surrounding said openings and releasably engaging said seats, and a thimble secured in one of said openings and provided with spaced external shoulders, one of said seat members provided with an internal flange extending between one of said shoulders and the section with which the thimble is associated, the bore of the seat member being sufficiently larger than the adjacent portion of the thimble to permit relative lateral movement between the thimble and seat member.

3. A coupling comprising separable sections, each section provided with separate passages, one of the sections being provided with openings communicating with its passages for connection with pipe lines, one of said sections being provided with ports communicating with its passages, the walls of

said ports being provided with seats, the other section being provided with openings communicating with its passages, seat members surrounding said openings and releasably engaging said seats, one of said seat members being loosely connected with the section with which it is associated so as to be self-adjusting to the seat that it engages, a yoke pivoted to one of the sections, the axes of said pivots extending in a plane that passes approximately midway between the seat members, and a screw in the yoke engaging the section not provided with pivots.

4. A coupling comprising separable sections, each section provided with separate passages, one of the sections being provided with openings communicating with its passages for connection with pipe lines, a means to clamp the sections together, one of said sections being provided with ports communicating with its passages, the walls of said ports being provided with seats, the other section being provided with openings communicating with its passages, seat members surrounding said openings and releasably engaging said seats, one of said seat members being loosely connected with the section with which it is associated, so as to be self-adjusting to the seat that it engages, and a guide projecting from one of the sections into position alongside of the other section for relatively positioning the sections, when being assembled, so as to approximately align the seat members with the seats.

5. A coupling comprising separable sections, each section provided with separate passages, one of the sections being provided with openings communicating with its passages for connection with pipe lines, a means to clamp the sections together, one of said sections being provided with ports communicating with its passages, the walls of said ports being provided with seats, the other section being provided with openings communicating with its passages, seat members surrounding said openings and releasably engaging said seats, one of said seat members being loosely connected with the section with which it is associated so as to be self-adjusting to the seat that it engages, a yoke pivoted at opposite sides to one of the sections, the axes of the pivots being positioned in a plane extending approximately midway between the seat members, and a guide on one of the sections positioned at approximately a right angle to said plane and extending alongside of the other section for relatively positioning the sections, when being assembled, so as to approximately align the seat members with the seats.

Signed at Los Angeles, Calif., this 1st day of March 1929.

HERBERT V. LEAHY.
